UNITED STATES PATENT OFFICE.

JOHN H. MOWEN, OF BROOKLYN, NEW YORK.

DESIGN FOR ORNAMENTATION OF BURIAL-CASKETS.

SPECIFICATION forming part of Design No. 16,387, dated November 17, 1885.

Application filed September 26, 1885. Serial No. 178,311. Term of patent 3½ years.

To all whom it may concern:

Be it known that I, JOHN H. MOWEN, a citizen of the United States, residing at the city of Brooklyn, in the county of Kings and State of New York, have invented a new and useful design for the Ornamentation of Burial-Caskets; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

This design relates to the ornamentation of burial-caskets or coffins; and the novelty consists in the form, shape, configuration, and effect of the molding or ornamentation placed thereon, as fully hereinafter described, and illustrated in the accompanying drawings, in which—

Figure 1 is an enlarged view of the molding in contrast with the side of the casket, which is ordinarily plain and somber. Figs. 2 and 3 are cross-sections, and Fig. 4 a side elevation of a casket with the molding on a smaller scale.

The essential feature of the design is a semi-columnar molding, having its face divided into squares and half-squares by depressions which run across the face of the molding in opposite directions and at regular intervals at about forty-five-degree angles with the plane of the molding. The squares are arranged with diagonally-opposite corners in the center and sides of the molding. Each square has an oval apex and four inclined sides, and each half-square has a crest or comb with sides sloping there-

from. The form given to the molding produces a variety of lights and shades, which contrast strikingly with the plain surface of the casket.

Referring to the drawings, A designates the body of the casket, and B the molding. At regular intervals the face of the molding is divided into squares C and half-squares D by depressions b, which cross the face at angles of forty-five degrees with the plane of the molding. These depressions are in double series and cross each other at the center. Each square or lozenge C has an oval apex, c, and four inclined sides, c', while the half-squares have each a ridge or comb, d, which is transverse to the longitudinal plane of the molding. In the depressions are arranged cords G, to intensify the effect, though the cords may be omitted without changing the essential features of the design.

Semi-columnar moldings are not new; but

What I do claim as new is—

The design for the ornamentation of a burial-casket herein described, which consists in the body A and molding B, the said molding having its face formed into squares C and half-squares D by depressions b, the squares C having each an oval apex and four inclined sides, and the half-squares having combs d, arranged transversely to the plane of the molding, with sides inclining therefrom, as shown and set forth.

In testimony whereof I affix my signature in presence of two witnesses.

JOHN H. MOWEN.
